UNITED STATES PATENT OFFICE.

WILBUR H. GEESMAN, OF YOUNGSTOWN, AND ARTHUR G. MCKEE, OF CLEVELAND,
OHIO.

METHOD OF AND MEANS FOR BURNING AIR AND GAS.

1,388,944.

Specification of Letters Patent. Patented Aug. 30, 1921.

Application filed October 31, 1917. Serial No. 199,504.

To all whom it may concern:

Be it known that we, WILBUR H. GEESMAN and ARTHUR G. MCKEE, citizens of the United States, residents, respectively, of 5 Youngstown, county of Mahoning, and State of Ohio, and Cleveland, county of Cuyahoga, and State of Ohio, have invented new and useful Improvements in Methods of and Means for Burning Air and Gas, of which 10 the following is a specification, the principle of the invention being herein explained and the best mode in which we have contemplated applying that principle, so as to distinguish it from other inventions.

15 Our invention relates to methods of and means for burning air and gas. Said invention is particularly applicable for use in connection with blast furnace operations or other operations where lean gases of a low

20 B. T. U. are utilized.

The object of the invention is to procure conveniently and economically a well mixed fuel, a short flame and very hot combustion.

The annexed drawings and the following 25 description set forth in detail certain steps and certain means embodying our invention, the disclosed steps and means, however, constituting but one of various methods and mechanical forms in which the principle of 30 the invention may be employed.

In said annexed drawings:

Figure 1 represents a central vertical longitudinal section of a gas burner embodying our improved means and an exemplification 35 of one way of carrying out the steps of our improved method, a suggestion of the ordinary blast furnace stove and foundation therefor being also shown; Fig. 2 represents a transverse vertical section, taken in the 40 plane indicated by the lines II—II, Fig. 1, the stove door being shown in its open position and the mixing apparatus in operative position relatively to said stove; Fig. 3 represents a side elevation, partially in section, 45 of certain elements of our improved means; Fig. 4 represents a side elevation of certain elements of our improved means, showing the same removed from operative relation to the stove and showing a suggestion of 50 the usual means for longitudinally moving the gas burner; Fig. 5 represents a central vertical longitudinal section through the stove door when the cover is closed thereover; and Fig. 6 represents an end elevation

of the combination shown in Fig. 5 and 55 taken from the right hand side of Fig. 2.

In the annexed drawings an exemplification of our improved burning means is shown in relation to a blast furnace, the usual stove of which is indicated by the ordinal 1, the 60 stove foundation being indicated by 1' and an annular casing by 1² which surrounds and lies adjacent to the stove door opening to which is fitted the usual cover as herein-after explained. There is provided a damper 65 controlled gas conduit 2 leading to the annular comparatively thin nozzle 3 surrounding the air nozzle 4, which is also damper controlled, as shown. Said nozzles 3 and 4 are designed to furnish gas and air to the 70 combustion chamber 5 of the stove 1. There is furnished to the chamber 5 an additional supply of air through an annular opening 6 surrounding the nozzle 3. Whenever it is desired to discontinue the furnishing of the 75 gas and air to the stove 1, the nozzles 3 and 4 are moved back away from the door of the stove 1 in the manner hereinafter described and the cover 7, carried by a hanger 8 in turn carried by suitable trolley wheels and also 80 supporting the spider 9 of the design plainly shown in Fig. 2, adapted to inclose the bolts 10 and to receive the hinged bolt 11, is swung into place. The means for moving the nozzles 3 and 4 relatively to the stove are provided 85 by the hand wheel 12 rotatably secured to a shaft 13 to which shaft is secured a pinion 14 adapted to engage with a rack 15 suitably supported. All of the aforementioned elements and their operation are 90 well known, with the exception of the features controlling the relative amounts of gas and air. To these well known elements we have applied our improved mixing means and new method of burning which will now 95 be described.

Secured to the outer surface of the air nozzle 4 by means of bolts 16' are auger-shaped baffling blades 16 forming a multiple thread helical screw, and slidably secured 100 upon the outer surface of the gas nozzle 3 by collar 18' and set screws 18² is an annular angle 18 to the projecting member of which are secured, by means of rivets 19, blades 17. Said blades 17 are of the general 105 design plainly shown in Fig. 4 and are inclined relatively to the axis of the nozzles 3 and 4, such direction of inclination being

transverse, and, in the embodiment of our invention herein shown, substantially opposite to the inclination of the blades 16.

The relative amount of air furnished to 5 the chamber 5 between the blades 17 can be regulated by adjusting the angle 18 upon the gas nozzle 3 so as to more or less close the annular opening 6.

By the means previously described, the 10 gas passing through the conduit 3 is given a rotary or whirling motion and passes into the chamber 5 in a helical or auger-shaped path, the air entering the chamber between the blades 17 being given a rotary or whirling motion in a direction substantially opposite to the path of travel of said gas. Violent eddy currents are thus produced between the gas and air, resulting in an immediate and intimate intermixture. Further air, if necessary, in 15 controlled amounts is furnished to the chamber 5 by the nozzle 4 in the general direction of travel of the gas in the conduit 3, which direction, of course, is longitudinally of the 20 nozzle 3. Our construction produces an annular ring of gas comparatively thin, from three to four inches, surrounded by air on both sides which of itself gives a better result than ordinarily secured. The 25 whirl in opposite directions given to the annular ring of gas and the surrounding annular layer of air very greatly enhances the speed and intimacy of the intermixture and results in an extremely short flame and combustion of great intensity.

What we claim is:

1. In means for burning air and gas, the 30 combination of a stove; a gas nozzle adapted to discharge into the same; an air inlet to said stove surrounding the discharge end of 35 said nozzle; means for imparting a whirling motion to the air; and means for imparting an opposite whirling motion to the gas, both of said whirling means terminating substantially in the plane at which the air and gas enter the stove.

2. In means for burning gas and air, the 40 combination of a stove; a gas nozzle adapted to discharge into the same; an air inlet to 45 said stove surrounding the discharge end

of said nozzle; auger-shaped baffling blades disposed in said nozzle and arranged so as to project the gas into the stove with a whirling motion; inclined blades intersecting said air inlet; a duct provided 55 interiorly of the gas nozzle and arranged with its discharge end in substantially the same plane as the discharge end of said nozzle; and means for controlling said duct.

3. In means for burning gas and air, the 60 combination of a stove; a gas nozzle adapted to discharge into the same; an air inlet to said stove surrounding the discharge end of said nozzle; auger-shaped baffling blades disposed in said nozzle and arranged so as 65 to project the gas into the stove with a whirling motion; inclined blades intersecting said air inlet; a duct provided interiorly of the gas nozzle and arranged to discharge longitudinally of the latter and with its discharge end in substantially the same plane as the discharge end of said nozzle; and means for controlling said duct.

4. In an improved method for burning air and gas, the steps which consist, in imparting to gas and air whirling motions in opposite directions; and then discharging them into a combustion chamber from substantially the same transverse plane, whereby violent eddy currents are produced between the gas and air.

5. In an improved method for burning air and gas, the steps which consist, in providing a comparatively thin annular ring of 85 gas; imparting thereto a whirling motion and discharging it into a combustion chamber; furnishing said chamber air interiorly of said gas ring, introducing into said chamber an annular layer of air exteriorly of said gas ring, said layer of air having imparted 90 thereto before entering said chamber a whirling motion in a direction opposite to the whirl of said gas.

Signed by me this 24th day of October, 1917.

WILBUR H. GEESMAN.

Signed by me, this 27th day of October, 1917.

ARTHUR G. MCKEE.
